HARROW ATTACHMENT HOOK COMPONENT
Rheinhard Bobrowski, Morris, Manitoba, Canada, assignor to Manitoba Development Fund, Winnipeg, Manitoba, Canada
Filed Dec. 21, 1964, Ser. No. 419,639
1 Claim. (Cl. 172—677)

My invention relates to new and useful improvements in harrow hook components which permit the harrow sections to be connected to a harrow draw bar or the like by means of chains.

Conventional hook components on harrow sections are normally open hooks having projecting corners or the like which permit the chains to become unhooked from the harrow sections particularly during turns.

Furthermore the corners on such hooks often are engaged by an additional link of the chain while turning thus upsetting the draft characteristics of the harrow sections.

I have overcome these disadvantages by providing a hook component preferably formed from a stamping and having a central aperture formed therein, the hook curving smoothly over and into the aperture with the distal end of the hook terminating substantially flush with the underside of the component so that a chain link has to be inserted within the aperture before it can be engaged on the hook.

This prevents undesirable disengagement of the chain and also prevents undesirable fouling of other links upon the hook component particularly when turns are made with the harrows.

The principal object and essence of the invention is therefore to provide a device of the character herewithin described which prevents undesirable disengagement of the chains from the harrow hooks.

Another object of the invention is to provide a device of the character herewithin described which is simply formed from a stamping thus making it extremely economical in manufacture.

A yet further object of the invention is to provide a device of the character herewithin described which provides means to support the strap normally transferring the load from the rear harrow member to the next adjacent member.

Still another object of the invention is to provide a device of the character herewithin described which is simple in construction, economical in manufacture, and otherwise well suited to the purpose for which it is designed.

With the foregoing objects in view, and such other objects and advantages as will become apparent to those skilled in the art to which this invention relates as this specification proceeds, my invention consists essentially in the arrangement and construction of parts all as herein-after more particularly described, reference being had to the accompanying drawings in which:

FIGURE 1 is perspective fragmentary view of a portion of a harrow showing my invention thereon.

FIGURE 2 is a top plan view of the attachment hook component.

FIGURE 3 is a side sectional elevation of FIG. 2 and showing the method of attaching the chain link to the hook.

In the drawings like characters of reference indicate corresponding parts in the different figures.

Proceeding therefore to describe the invention in detail, reference character 10 illustrates the front transverse frame member of a harrow and 11 the next adjacent frame member, said frame members being maintained in spaced apart relationship by means of the cross members 12.

2

It will be appreciated that this is only one section of a harrow, but as the other sections are similar, it has not been deemed necessary to illustrate same.

It should also be appreciated that although the portion 5 of the harrow illustrated is what is known as a diamond harrow, nevertheless the attachment component can be utilized with any type of harrow.

My device collectively designated 13 comprises a substantially rectangular stamping 14 being provided with a centrally located aperture 15. The walls 16 bounding the aperture form a substantially rectangular aperture clear through the stamping and a hook 17 is also formed integrally with the stamping and extends from the side edge 18 thereof. This hook curves upwardly over and towards the center of the rectangular stamping 14 as shown in FIG. 3 and the distal end 19 of the hook terminates substantially centrally within the aperture 15 and substantially in the plane of the undersurface 20 of the stamping as clearly shown in FIG. 3.

20 A pair of lugs 21 are also formed integrally with the stamping upon the opposite side edge 22 to the edge 18, said lugs inclining upwardly and outwardly.

A strap 23 is bolted to the next adjacent frame member 11 of the harrow and extends diagonally towards the frame member 10 to which it is also bolted together with the hook component 13 by means of bolt 24 extending through the component, through the strap 23, and through the member 10. The strap nests between the lugs 21 thus giving stability to the hook component and preventing same from pivoting with relation to the frame member 10.

25 In operation, the chain link 25 is inserted within the aperture 15 so that it is engaged over the distal end 19 of the hook 17. It is then rotated through the arc indicated by arrow 26 to take up the position shown in phantom in FIGURE 3.

30 This means that it is almost impossible for the hook to be disengaged inadvertently during the turning operation.

40 The smooth contour of the outer surface 27 of the hook also prevents undesirable entanglement of the other chain links, an occurrence prevalent with conventional hooks due to the turning operation.

45 Since various modifications can be made in my invention as hereinabove described, and many apparently widely different embodiments of same made within the spirit and scope of the claim without departing from such spirit and scope, it is intended that all matter contained in the accompanying specification shall be interpreted as illustrative only and not in a limiting sense.

50 What I claim as my invention is:

55 The combination of a harrow frame having first and second frame members spaced from each other, and a draft attachment comprising a strap extending across said first and second frame members, a draft member formed integrally from one piece of material and comprising a plate provided with a rectangular aperture whereby the plate forms a pair of side pieces and front and rear pieces at the sides and front and rear of the aperture respectively, a curved hook provided integrally centrally on the front edge of the front piece and extending upwardly and rearwardly and then downwardly to a free terminus disposed substantially centrally in said aperture and substantially flush with the underside of said plate, said hook being adapted to receive a link of a draft chain inserted in said aperture and passed upwardly over said free terminus and then forwardly to the front portion of said hook, the rear piece of said plate being superposed on the first frame member of the harrow frame and underlying one end portion of said

trap, a single fastening element extending through said one end portion of the strap and through said rear piece of the plate and through said first frame member whereby to provide sole means for securing the same together, another fastening element securing said strap to the second frame member of the harrow frame in spaced relation from the first mentioned fastening element, and a pair of transversely spaced upturned lugs provided integrally at the rear edge of the rear piece of said plate in alignment with said side pieces thereof, the transverse spacing of said lugs being such that they abuttingly engage the opposite sides of said one end portion of

said strap and the latter thereby prevents said draft member plate from turning about said single fastening element constituting said sole securing means.
